Assignor to

The Lowell Manufacturing Company.

Letter Patent No 1723, dated Mar, 3, 1863.

The schedule referred to in these Letters Patent and making part of the same

To all whom it may concern:

Be it known that I, Eliot J. Key, of Lowell, in the County of Middlesex and State of Massachusetts, now temporarily residing in New York, have originated and designed a new pattern for carpets or other fabrics, of which the following is a full clear and exact description, reference being had to the accompanying drawings, making part of this specification.

A. is a large oblong set figure resting on the ground 1, which is enclosed by a frame, 2, composed of combinations of Persian figures. Band C, at the sides, not even matched, forms a figure similar, in form, to fig A, and with similar surroundings. Figs 3 and 4, are composed of narrow frames enclosing a number of small cross-shaped blocks. Band 6, at the sides are halves of figures similar to Band 1.

B, at the top is a section of a figure similar to A. E and F, in the lower corners are sections of figures similar to figs B, and C. The remainder of the design consists of a ground work of figures of a Persian style.

The colors employed for the different portions of the design may be varied to suit the taste and wish of the manufacturer.
